[57] CLAIM

The ornamental design for a logo panel cap, as shown.

DESCRIPTION

FIG. 1 is a front elevational view of a logo panel cap showing my new design;

FIG. 2 is a rear elevational view thereof;

FIG. 3 is a right side view of the logo panel cap of FIG. 1; FIG. 4 is a left side view of the logo panel cap of FIG. 1; FIG. 5 is a top plan view of the logo panel cap of FIG. 1; FIG. 6 is a bottom plan view of the logo panel cap of FIG. 1; and,

FIG. 7 is a top, front, right side perspective view of the logo panel cap of FIG. 1.

The broken line showing of panel in FIG. 7 is for illustrative purposes only and forms no part of the claimed design.
